UNITED STATES PATENT OFFICE.

COULTER D. HUYLER, OF GREENWICH, CONNECTICUT, ASSIGNOR TO HUYLER'S INC.,
OF NEW YORK, N. Y., A CORPORATION OF NEW YORK.

DESIGN FOR A JAR.

56,252.

Specification for Design.

Patented Sept. 7, 1920.

Application filed January 2, 1920. Serial No. 349,060. Term of patent 14 years.

To all whom it may concern:

Be it known that I, COULTER D. HUYLER, a citizen of the United States, and resident of Greenwich, county of Fairfield, and State of Connecticut, have invented a new, original, and ornamental Design for Jars, of which the following is a specification, reference being had to the accompanying drawings, forming part thereof.

Fig. 2 is a cross section on the line 2—2 in Fig. 1.

I claim:

The ornamental design for a jar, substantially as shown.

Signed at New York, county of New York and State of New York, this 23d day of December, 1919.

COULTER D. HUYLER.
